UNITED STATES PATENT OFFICE.

THOMAS E. CLARK AND JAMES E. CLARK, OF DETROIT, MICHIGAN, ASSIGNEES TO
CONTINUOUS TRAIN CONTROL CORPORATION, OF DETROIT, MICHIGAN, A CORPORATION OF MICHIGAN.

TRAIN-CONTROL SYSTEM.

Application filed April 6, 1925. Serial No. 21,171.

This invention relates to the control of railway trains by means of radio or other high-frequency currents propagated in the track rails which are divided into blocks, generators and transmitters of high-frequency currents being provided for each block and being of such character that induced currents may be taken up by proper receiving devices on the locomotive or other designated vehicle. The object of this invention is to provide high-frequency generators and transmitters which will propagate and impress currents of different frequencies in or upon the rails of each occupied block, one current being propagated and impressed when the track is clear for two blocks ahead of the occupied block, another similar current when the second block in advance is occupied, and a third similar current to one of the rails whenever the block in question is occupied, neither the first nor the second current being propagated when the block in advance is occupied, the induced current resulting from this third current serving to control devices on the locomotive which will unlock the speed controlling elements and mechanisms governed and controlled by the induced currents resulting from the other two currents impressed upon the rails. In carrying out this invention the wires which convey the high-frequency control currents to be propagated and impressed upon the rails for the purpose of governing and controlling the speed of the locomotive under "clear" or "caution" conditions, are preferably connected to the rails at the exit ends of the several blocks into which the track is divided, or may be divided, and the length of track which will be traveled by these control currents before they become too weak to produce currents by induction of sufficient strength to actuate the instrumentalities on the locomotives, will depend upon the character of the generating and transmitting apparatus and the track structure. We have found that a portion of the track at the entrance ends of long blocks may be free from control currents where the track is laid in open country, so that a track equipped with our present invention will have some of the characteristics of the "ramp" or conductive systems of train control in that the governing currents will be

received by the locomotive at separate intervals, during at least a portion of which the control mechanism on the locomotive is unlocked and in condition to be governed by the induced current thus received, the instrumentalities being locked after such reception during the time the locomotive is moving to the controlled portion of the next block.

Our present invention, which makes use of the track rails as its energy transmitting agents and arranges for such energy to be picked up by induction, might be termed an invisible ramp system, but it has certain advantages over such ramp and conductive systems as have been heretofore proposed in that it avoids the serious objections to these systems due to the failures and breakdowns to which they are liable, particularly the failures to transmit currents when their transmitting elements are covered with sleet, ice, dirt or other insulating materials, and when the transmitting elements are moved or otherwise disturbed so as to be out of adjustment and therefore fails to produce proper contacts with the predetermined parts on the locomotives.

Our present invention is furthermore designed to make use of or to be co-ordinated and used in connection with railroad signal systems of any type, the type shown being of the "approach light" type, that is, one in which the signal lights at the exit ends of the occupied blocks only receive current, and the track wires which supply current to these signal installations are employed to supply current to the control installations. We have so designed the control installations that no current is transmitted to the rails of unoccupied blocks and that should any transmitting installation fail to function, the result will be "danger" or stopping indications within the locomotive cab.

We have further so designed the control mechanism on the locomotive that should the conditions of the track ahead require slackening or stopping of the train, the application of the brakes by this mechanism will occur but will be gradual so as to avoid jolts and jars as far as possible.

Our invention is pointed out in the here-to annexed claims and is shown conventionally and diagrammatically in the ac-

companying drawings, in which Fig. 1 is a diagram of the electric circuits on a vehicle equipped with this novel train control mechanism. Figs. 2 and 2^A are diagrams of the 5 brake controlling mechanism shown in two positions. Fig. 3 is a diagram of a control station. Figs. 4^A to 4^E inclusive are diagrams of signal and control installations showing the parts under various track conditions, Figs. 4^A, 4^B and 4^E also showing diagrams of the vehicle installation under these conditions. Fig. 5 is a diagram of a track signal installation. Fig. 6 is a diagram of an installation adapted for the end 10 of a controlled track and at the entrance of a non-controlled track.

Similar reference characters refer to like parts throughout the several views.

We have taken advantage of the fact 20 that the ordinary direct currents employed for actuating and controlling trackway signals have no effect upon the propagation of or transmission in the rails of radio high-frequency currents, and that these radio 25 high-frequency currents have no effect upon the direct track current or circuits nor any effect upon other radio frequency currents of different wave lengths, so that we use the track rails to simultaneously carry several 30 of the radio frequency currents and a direct current.

The signal system shown in the drawings forms no part of the present invention as 35 a signal system, but parts thereof are used as part of the train control system, and in order to fully comprehend the control system, the signal system must be understood. The signal system embodies a multiple-lamp stand at the entrance end of each block, each 40 stand comprising red, yellow and green lamps to indicate danger, caution and safety conditions in said blocks; that is, to indicate that the next, or the second block in advance is occupied or that neither is occupied.

Each block is provided with a "track" 45 battery at the entrance end and with a holding relay at the exit end, both connected to the rails, this relay while energized holding up an armature. Whenever a locomotive or other vehicle enters the block 50 and electrically connects the rails, and thereby shorts the circuit to the relay, the armature falls and closes the circuit to a signal lamp at the entrance to the next block 55 in advance, so that the engineer has constantly before him a light indicating the condition of the block in advance. The holding relay requires a minimum of current, much less than is required by the light 60 bulbs. The only lights showing are at the exit ends of occupied blocks. The character of each light is controlled by the adjacent installation, which, in turn, is influenced by the signal installation of the block in advance. Thus, if a track is divided into 65

blocks equipped with the installations illustrated, and the direction of traffic is from block A to block D, that is, to the left, and block D is occupied, upon the approach of a train a red light will show at the entrance 70 end of block D, a yellow light at the entrance end of block C, and a green light at the entrance ends of blocks B and A.

The several parts of the installations shown in Figs. 4^B to 4^D inclusive are in the 75 positions which they assume when block D is occupied at T (Fig. 4^E) and with at least two blocks ahead of T unoccupied.

Figs. 4^A to 4^E inclusive show two wires 1 and 2 connecting adjacent signal installations. When no current flows over wires 1^D and 2^D, as is the case when train occupies block D, a red lamp R will be ready to burn at the entrance of block D; plus current flows over wire 2^C from installation D to 80 installation C and back over the wire 1^C, and a yellow lamp indicating caution will be ready to burn at the entrance of block C; plus current flows over wire 1^B from installation 85 C to installation B and back over wire 2^B, and a green light indicating "clear" will be ready to burn at the entrance of block B. These lights will burn as soon as the 90 blocks leading to them are occupied, but no light is shown unless the block is thus occupied. For the sake of simplicity, the wire 95 2 will be disregarded and the current over wires 1 and 33 to the polar neutral relay 34 will be considered as plus or minus, as this nomenclature fits the movements of the 100 armature 34^B, which swings to the left in the drawings under plus current and to the right under minus current passing to the relay 34.

Each signal installation shown in the 105 drawings comprises two batteries, two neutral relays, one of them the holding relay, and a polar-neutral relay. The energy for both the signal and control systems is derived from the wires 3 and 4 which extend 110 along the track and may be considered to carry 440 volts A. C., which is often used in railway signal systems. Extending from these wires 3 and 4 are wires 5 and 6 which 115 connect to the fine winding of a transformer 7 which steps down this current to about 110 volts for battery charging. Wires 8 and 9 lead from the transformer 7 to the rectifier 10 for the track battery 12 to which current 120 is carried by the wires 13 and 14. A second rectifier 15, connected to the wires 8 and 9 by the wires 16 and 17, supplies current 125 to the signal battery 18, wires 19 and 20 connecting this battery to the rectifier. These rectifiers may be of any desired construction.

The track battery 12 connects to the rails 21 and 22 by means of wires 23 and 24, the resistances 25 and 26 being interposed to protect the track battery from damage when the 130 rails are short circuited by a train. The

function of this track battery is to energize the relay 27 of the next installation in advance, which holds up certain armatures 27^a—b—c—d, which armatures engage front contacts to close circuits which govern the adjacent train control installation and also the signaling installation of the next block in the rear. When this relay 27 is deenergized, its armature d closes a circuit which is common to all the lamps R, Y and G of the adjacent signal post. When, therefore, a block is occupied, the armature of this relay 27 closes one of the circuits to the signal lamps at the exit end of the block, and this results from the short circuiting of the track battery of that block. The particular signal bulb which is to burn is controlled by the wires 1 and 2 and the signal installation of the next block in advance.

A train T being in block D (Fig. 4^a), the relay 27 of that block is deenergized and no current flows from the signal battery 18 to the signal installation at the entrance of block D because the armature 27^c has left the contact at the end of wire 29 connecting to the track signal wire 2. There is then, no current in the wires 32 and 33 leading from the track wires 1^a and 2^a to the relay 34 of the signal installation D at the entrance end of block D. The polar neutral relay 34 of station D, therefore, is not energized and its armature 34^a breaks contact with the point 35 which results in the circuit to the relay 36 being broken and the armatures 36^a—b—c falling to engage their back contacts. When these parts are thus positioned, the following circuits are established.

From the minus end of battery 18^D over the wires 19, 44 and 43, armature 36^c, wires 30 and 1^c to installation C, wire 33 to polar neutral relay 34 which is energized negatively to cause the armature a to engage contact 35 and armature b to engage the contact 51. From the relay 34, this negative current flows over wire 32 to wire 2^c, wire 29 at installation D, armature 27^c, wire 42, armature 36^b, and wires 39, 38, 37 and 20 to the battery.

The wire 45 from the bottom of the signal post 40 is always connected to the battery 18. The wire 46 to the red or danger lamp R ends at the back contact engaged by the armature 36^a which is at one end of the wire 46. The wire 47 extends from the armature 36^a to the armature 27^d which is held up from its back contact so long as the track relay is energized. But as soon as the block C is occupied, and the relay 27 is deenergized, then this armature will drop and close the circuit to the wires 48 and 19 to the battery, causing the danger signal R to become lighted. In other words, the danger signal is ready to become lighted as soon as a train enters block C.

We have now a "caution" or negative current in track wire 1^c, which flows over the

wire 33 to the polar neutral relay 34 of station C and back to station D over the wires 32 and 2^c. The polar armature 34^b swings counter-clockwise and the neutral armature 34^a also engages the contact 35 at the end of the wire 49 which closes the circuit to the relay 36. Positive current flows from the battery 18 over the wires 20, 37, 38 and 39, armature 36^c and wire 30 to the track wire 1 to the signal installation at the entrance of block 4^B, then back over wire 2 and wire 29, armature 27^c, wire 42, armature 36^b, and wires 43, 44 and 19 to the battery. This, therefore, is the control circuit for the next indication in the rear.

The circuit for the signal indication at this installation C is as follows: from the battery 18 over wires 20, 37 and 45 to the signal stand and to the caution yellow lamp Y, then over 50 to the contact 51, armature 34^b, wire 52, armature 36^a, wire 47 to armature 27^d. This is, however, held up until a train enters block B and therefore the yellow light does not show until a train shorts the circuit to relay 27^c.

The control current for block B is positive and flows from the battery 18^C over wires 20, 37, 38 and 39, armature 36^c, and wires 30 and 1^B to polar neutral relay 34 at station B over wire 33, and thence to wire 2^B over wire 32. The neutral armature 34^a engages the contact 35 on wire 49 as described in connection with station C, while the polar armature b engages the contact 54 at the end of wire 55 which connects to the green lamp G on the post 40. The return circuit to the battery has been described. A train T is shown in block A so that relay 27^B is short circuited and the signal G at station B therefore becomes lighted.

The mechanism thus far described is not new. At each signal installation or station a train control installation is established which connects to the rails of the block leading to that station and each control installation embodies two transmission devices for propagating radio or other high-frequency currents to the rails, one of the transmission devices generating current of greater frequency and lesser wave length than the other. It is immaterial which of the two is used for "caution" and which for "clear" conditions, so long as the same current is used throughout the entire track for "caution" conditions and the same current for "clear" conditions.

A pair of wires 60 and 61 extend the length of each block and wire 61 connects to the wire 2 of the block in advance by means of a wire 62. Each wire 60 connects to the wire 1 of the block in advance so long as the relay 27 at the station between these blocks is energized, this connection consisting of the wire 63', armature 27^c and wires 64' and 33.

A control installation embodying two transmitting devices, is installed at the exit end of each block and delivers radio or other high-frequency currents of three different wave lengths, one of the transmitting devices being connected to one of the rails by two wires so that a portion of this rail or zone is in circuit therewith, while the other transmitting device is connected to both track rails, nearer the exit end of the block than the first named device. The first device is termed the unlocking installation. The second device, termed the control installation, is adapted to impress radio waves of either of two wave lengths upon the rails, the distance such current will flow along the rails toward the entrance end depending upon the character of the transmitting device, but it is desirable to use currents which will be operative at some distance beyond the unlocking zone.

The currents from the unlocking and from the control installations in any block depend upon the condition of the second block in advance, and while any desired wave lengths may be employed, 2500 meters wave length and a frequency of 120,000 has been found to be a suitable current for the unlocking current, 5500 meters and a frequency of 54,600 for the "caution" current and 6500 meters and a frequency of 46,200 for the "clear" current. Proper instrumentalities to be described later on are installed upon the locomotives or other suitable vehicles and embody devices influenced by the control currents for determining the speeds of the locomotive under "clear" and "caution" conditions. These instrumentalities are unlocked while the locomotive is passing the unlocking zone and respond to the control currents, being locked when the locomotive passes out of the locking zone. The locking zone is preferably about 300 feet long which is also the preferred distance between it and the exit end of the block.

The unlocking and the control devices operate only when the block to which they are connected is occupied. The train control installation does not operate to transmit current to the rails when the red lamp at the exit end of the block signals danger conditions for the next block, but when the yellow or green lamp at the exit end of the block occupied by the locomotive signals "caution" or "clear" conditions for the next block in advance, the rails of the occupied block will receive current of either 5500 or 6500 meter wave length.

The several drawings Figs. 3 and 4^A to 4^E inclusive show two relays 63 and 64, the former a polar neutral relay having armatures *a*, *b* and *c*, and the latter a neutral relay having armatures *a* and *b*. The former governs the clear or caution indications and

speed-control installation and the latter, the locking circuit and the other installation.

Referring now to Fig. 4^E, the control wires 60^E and 61^E are observed connecting to the wires 65 and 66. The track for at least three blocks in advance is clear so that plus current flows over the wires 60^E and 65 to the relay 63 and over wires 66 and 61^E back to the next signal installation in advance. The plus current energizes the relay 63 which attracts the armatures *a* and *b* and swing the polar armature *c* to the left.

Wires 67 and 68 connect the track power wires 3 and 4 to the primary winding of a transformer 69 and wires 70 and 71 connect to the secondary winding of said transformer and end at the contacts 72 and 73. The normal circuit of the relay 64 is from the signal battery 18 over wires 20, 37, 45 and 74 to relay 64 and then back by wire 75, armature 27^a, wires 76, 31, 48, 44 and 19 to the battery. But the train T is in block D so that the relay 27 is short circuited and therefore does not hold up armature 27^a, resulting in relay 64 being de-energized and the relay armatures 64^a and 64^b engaging the contacts 72 and 73.

The control installations are shown conventionally in Figs. 4^A to 4^E inclusive but such an installation is diagrammatically detailed in Fig. 3, the positions of the parts being those assumed when the block, in advance and its own block are unoccupied. When the block of this control station shown in Fig. 3 is occupied, 110 volts A. C. current from the transformer 69 passes over the wires 70 and 71, armatures *a* and *b* of the then de-energized relay 64, and wires 76 and 77 to the primary 78 of the alternating current transformer 79. The secondary 81 of this transformer connects to the plate element 82 of the electron tube 83 by the wire 84, and to the inductance 86 by wire 85. The winding 84 is shunted by the by-pass condenser 87. The wire 88 connects to the inductance 86 and to the grid condenser 89 and grid leak 90, while a wire 91 completes the circuit to the grid element 92, the inductance 86 being shunted by a tuning condenser 94. An auxiliary winding 95 of the transformer 79 connects to the filament 96 of the electron tube 83 by a wire 97 and to a rheostat 98 by means of a wire 99. A wire 100 connects one side of the filament 96 to a slide contact 102 on the inductance 86, accurate tuning being provided for by the variable condenser 103 between the wires 100 and 85 the wire 104 forming the connection. An adjustable contact 105 on the inductance 86 and a wire 106 lead to the rail 21 while a wire 107 connects this rail to the grid end of the inductance. Whenever therefore a train is in the block controlled

by this installation, and shorts the relay 21^D to the relay 63^D (Fig. 4^D) and this relay being de-energized, its armatures *a* and *b* break the circuit to the tube 120 which results in no current flowing over the wires 145—146 to the rails 21 and 22^C which produces a "danger" condition in these rails, the results of which will be to close the circuit over wires 1^D—33—64', armature 27^b and wires 63' and 60^C, but because of the train T in block D, no current passes over wire 1^D 75 so that no current passes over wire 60^C. Therefore, no current passes over wire 65 to energize relay 63 of station C and no control current passes to rails 21^B and 22^B. The result is that "danger" conditions prevail 80 not only in block D but also in block C within the distance influenced by the transmitter 120^C.

The control transmitter also embodies a transformer 110 having a primary 111, an auxiliary winding 112 and a secondary 113. The primary connects to the contacts 114 and 115 by means of wires 116 and 117, and the armatures 63^a and 63^b and wires 118 and 119 connect these contacts to the armatures 64^a and 64^b. The auxiliary winding 112 connects to the filament 120 of the electron tube 121 by means of the wires 122 and 123 and the rheostat 124, and the filament is thereby heated.

The secondary 113 connects to the grid element 125 by means of the wire 126, the inductance grid coil 127, grid condenser 128, grid leak 129 and wire 130. It also connects to the plate element 132 by means of the wire 133, variable condenser 134 and wire 135, the condenser 134 serving to tune this inductance circuit. The secondary 113 is shunted by a by-pass condenser 136, and the inductance plate coil 137 connects to the wires 133 and 135. A wire 138 connects the wire 135 to the polar armature 63^c which engages its back contact 139 when negative current energizes the relay 63, which occurs when "caution" conditions are indicated at the adjacent signal installation, and engages its front contact 140 when positive current energizes this relay, which occurs when "clear" conditions are indicated at this signal installation. A wire 142 connects the contact 140 to the wire 133, the variable condenser 143 serving to tune this plate coil 137 to the exact wave lengths desired for "clear" conditions.

The third inductance coil 144 is connected to the rails 21 and 22 by the wires 145 and 146, the series condenser 147 preventing this inductance from short-circuiting the rails and the track battery 12 at the opposite end of the block. In Figs. 4^A to 4^E inclusive, most of the details of the control installations are omitted, the electron tubes and the inductances being indicated by the reference characters of the tubes alone.

Positive current is passing over the wire 60^E (Fig. 4^E) to the relay 63 so that its armatures *a* and *b* are attracted and armature *c* is swung to the left. As track D is occupied at T, track battery 12^D is short-circuited at that point and relays 27 and 63 are de-energized so that an unlocking current passes to the rail 21^D over wires 106—107 and a long wave-length or "clear" current passes to the rails 21^D and 22^D over the wires 145—146.

As the relay 27 is de-energized, its armature *b* breaks the circuit 1^E, 33, 64, 63, 60^D so that no current passes over the track wire

being de-energized, its armatures *a* and *b* break the circuit to the tube 120 which results in no current flowing over the wires 145—146 to the rails 21 and 22^C which produces a "danger" condition in these rails, the results of which will be to close the circuit over wires 1^D—33—64', armature 27^b and wires 63' and 60^C, but because of the train T in block D, no current passes over wire 1^D 75 so that no current passes over wire 60^C. Therefore, no current passes over wire 65 to energize relay 63 of station C and no control current passes to rails 21^B and 22^B. The result is that "danger" conditions prevail 80 not only in block D but also in block C within the distance influenced by the transmitter 120^C.

A negative current flows over wire 1^C as previously explained and passes over wires 33 and 64' (Fig. 4^C) armature 27^b, wires 63^B and 60^B to station B and wire 65 to relay 63 which is negatively energized to attract its armatures *a* and *b* and swing its armature *c* away from the contact 140. As track A is occupied at T, relay 64 is de-energized and the circuit to transmitter 120 is closed resulting in short wave length or "caution" current being impressed upon rails 21 and 22^A.

The conditions at station A are similar to those of station D, except that a train T occupies the next block in the rear and that therefore the danger lamp R is giving its signal. The train T in Fig. 4^A is therefore receiving both the visual track signal and the cab signal which will be explained later on. The engineer of the train T (Fig. 4^B) has been seeing the "clear" signal G and has had a "clear" signal in his cab until he reached the unlocking zone of rail 21^A, when he received the "caution" signal in his cab which he carried all through block 4^B until he reached the unlocking zone of that block (Fig. 4^C). At this point he received the "danger" signal in his cab just prior to seeing the signal R ahead, and this "danger" signal indication as he enters block C affects the other instrumentalities on the locomotive and compels the train to stop. This mechanism will now be described.

The receiving apparatus.

On the locomotive, motor car or other convenient location is installed a current receiving and brake controlling mechanism which is shown generally in Fig. 1 and on a smaller scale in Figs. 4^A, 4^B, 4^E and 6. This installation comprises four collector loops or coils, a tuning condenser and a proper high-frequency relay for each coil, and three signal lamps to respectively indicate "clear", "caution" and "danger" conditions ahead. It also comprises certain neutral relays controlled by the high fre-

quency relays and armatures for these neutral relays whereby the circuits between a current source and a brake controlling valve may be opened and closed. It further comprises a governor for opening these circuits whenever the speed of the vehicle exceeds that which is permitted for "caution" or "danger" conditions.

The fact that the indications in this vehicle installation are fixed at the exit end of each block for the block in advance must be kept in mind. When the vehicle T, Fig. 4^p crosses the point where the wire 107 connects to the rail 21^a, one of the collector coils takes up an induced current, and an unlocking neutral relay in the vehicle is energized and its armatures close the circuits necessary to take advantage of the induced current taken up from between the rails by proper coils on the vehicle and resulting from the currents carried to these rails by the wires 145 and 146.

The several coils which take up the induced currents adjacent to the rails are marked 201, 202, 203 and 204 in Fig. 1. The loop 204 and the high-frequency relay connected thereto are used only when the locomotive passes from a track equipped with this control system to a track not so equipped and will be explained later on. The loops are connected to tuned high-frequency relays 205, 206, 207 and 208 respectively by means of wires 209, adjustable tuning condensers 211, 212, 213 and 214 being installed in these circuits. Four signal lamps 216, 217, 218 and 219 are preferably green, yellow, red and white, and indicate "clear", "caution", "danger" and "un-equipped track way" conditions respectively. A common wire 294 connects to these several lamps and to the wire 295 which connects to a normally closed switch 297 (Fig. 2) from which a wire 298 connects to one end of the battery 293.

This battery may be charged by a generator 285 which connects to the battery by means of wires 286 and 290, and which energizes the core of the magnet 287 to draw the switch armature 288 against the contact 289, thus closing the circuit 290 to the battery. Any other desired means may be employed to do this work.

The brake system embodies a solenoid 308, (Fig. 2) which, when de-energized, permits the application of the brakes, but so long as it is energized, holds the brake system inoperative. Therefore, so long as a current passes over the wire 296 to this solenoid 308, no automatic application of the brakes will occur.

The high-frequency relays 205 to 208 control neutral relays 221, 222, 223, and 224 respectively, (of which all but the first are stick-relays) each of which has a three part armature, the parts of which are lettered *a*,

b and *c*. The high-frequency relay 205 has an armature *a* to close the circuit from battery 293, wire 292, wire 225, relay 221, wire 226, armature 205^a, wires 227, 228, 229, 295, switch 297, and wire 298 to the battery. 70 This causes relay 221 to bring its armature *a* up to close the following circuit:—wires 225, 230 and 231, relay 224, wire 232, armature 221^a and wires 233, 228, etc., back to the battery. This causes the battery to energize 75 the relay 224 which lifts its armatures *a*, *b* and *c*. The train installation is now in condition to be positioned for "clear", "caution" or "danger" conditions in the block ahead. When "clear" conditions exists, the relay 206 80 receives current and the armature 206^a closes the circuit to the relay 222 which is from the wire 225 over wire 230, armature 224^a, wire 235, relay 222, wire 236, armature 206^a and wire 228 back to the battery via switch 85 297. The relay 222 then attracts its armatures. This circuit continues until the loop 201 ceases to receive current and the relay 221 becomes de-energized and the armature 221^a falls to complete the following circuit:—wire 235, relay 222, wire 237, armature 222^a, wire 238 armature 221^a and wires 233 and 228 to battery via switch 297. This circuit will continue until the relay 221 is again energized. A portion of the current 90 passing from the battery over wire 235 branches off over armature 222^b and thence passes over the wire 239 to green lamp 216 and back to the battery via switch 297.

The stick relay 224 also receives a continuous current from wires 225, 230 and 231 which flows over wire 241, armature 224^a, wire 242, armature 208^a, to wire 229 and back to the battery via switch 297. When the relays 222 and 224 are thus energized, 105 current flows from the wire 235, armature 222^a, wires 243 and 244, armature 224^b and wire 296 to the solenoid 308 which will be therefore energized whenever both relays 221 and 222 are energized. The 110 high-frequency relay 206 receives current at the exit end of the block only and is therefore de-energized most of the time, its neutral relay 222 being kept energized by the current that passes from the wire 235, relay 222, wire 237, armature 222^a, wire 238, armature 221^a and wires 223 and 228 to the battery via switch 297. Whenever therefore this relay 221 is again energized at the exit end of the next block, it releases the 115 relay 222. The parts are therefore in condition to receive control from the current received over the wires 145—146 at that exit end.

If "caution" current is received over loop 120 203, condenser 213 and relay 207, the circuit will be as follows, always remembering that the relay 221 is also energized because of the unlocking current and that relay 224 is also energized. The armature 207^a will close the 130

circuit from the wire 235 over wire 246, relay 223, wire 247 to wires 228 and 229, causing the relay 223 to be energized to draw its armature against the contact at the end of 5 wire 248, and at the instant the relay 221 is de-energized the following circuit is produced: from wire 235 over wire 246, relay 223, wire 248, armature 223^a, wire 249, armature 221^b, and wires 233 and 228 back to the 10 battery via switch 297.

This keeps the relay 223 energized until the unlocking circuit again functions, but while it is energized current flows over wire 235, armature 222^b, wire 250, armature 223^b 15 and wire 252 to the yellow lamp 217. Current also flows over wire 235, armature 222^a, wire 253, armature 223^a, wire 254 to the movable contact 255 of the governor 256 which may be constructed as shown in our prior 20 application, Ser. No. 719,002, filed June 9, 1924. In this construction, contact 255 remains in engagement with the contact 257 until the locomotive exceeds a predetermined speed, say 20 miles per hour, and if it exceeds this speed, will swing out of contact, 25 as shown in Fig. 1. From contact 257 current flows over wires 258 and 244, armature 224^b and wire 296 to solenoid 308. So long therefore as the train does not exceed the 30 predetermined speed and "caution" conditions exist in this control installation, current flows to solenoid 308. The governor 256 has a second movable contact 260 which controls the speed permissible under "danger" conditions, say four miles per hour, at which speed this contact 260 disengages the contact 257. But at lower speeds these contacts remain in engagement.

As stated before, the relay 221 is energized 40 at the exit end of each block and the relay 224 is always energized at the same time. If no current is received by either loop 202 or 203, "danger" conditions exist in the next block ahead and the relays 222 and 223 are 45 de-energized. Current flows from wire 235 over armature 222^c, wire 253, armature 223^c, wire 262, armature 221^c and wire 263 to the movable contact 260, and while the speed of 50 the train is not greater than that predetermined for "danger" conditions, the current flows from contact 257 over wires 258 and 244, armature 224^b and wire 296 to solenoid 308.

We have therefore an installation adapted 55 to take up three induced high-frequency currents of different wave lengths, one to cause the unlocking of the neutral relays and their armatures, a second to influence the "caution" relay, and the third to influence the 60 "clear" relay. An absence of both the two latter currents influences the parts to assume "danger" positions. When the parts are in "clear" positions, the solenoid 308 is always energized. When in "caution" positions this 65 solenoid is energized so long as the two contacts

255 and 257 of the speed governor engage; and when in "danger" positions, this solenoid is energized so long as the two contacts 260 and 257 engage.

When a portion of the track is not 70 equipped with the train control apparatus above described, a track installation such as is shown in Fig. 6 may be connected to the exit end of the last controlled block. Wires 270 and 271 connect the transformer 272 to 75 the wayside power wires 3 and 4 while the wires 273 and 274 connect this transformer to the transmitter 275 of high-frequency current of a different wave length than that of any of the currents transmitted over the 80 wires 106—107 or 145—146. Armatures *a* and *b* of the relay 276 control the circuits of this transformer and this relay is controlled by the track relay 27 as follows:—

So long as this block is unoccupied, this relay 27 is energized by the track battery 12 at the next installation in the rear, but when the train T short circuits this relay, it becomes de-energized and its armatures *a*, *b* and *c* drop to disengage their front contacts. The relay 276 is normally energized by a current flowing from the battery 18 over wires 37, 45 and 277 to this relay and over wire 278, armature 27^a, wires 31, 44 and 19 back to the battery. But when the relay 27 is de-energized, this circuit is broken and the armatures 276^a and 276^b close the circuit between the transformer 272 and transmitter 275 and this results in high-frequency current flowing to the rail 22 over the wires 280 100 and 281, so that an induced field is just above the section of the rail between these wires where it may affect the collector coil 204 whose condenser 214 is properly tuned for the wave length of this induced field. When 105 this occurs the relay 208 (Figs. 1 and 6) permits its armature *a* to break the stick circuit to relay 224 which permits its armatures *b* and *c* to engage their back contacts. The circuits which are closed thereby are from the battery 293 over wires 225 and 230 to the contact 282, armature 224^b and wire 296 to the solenoid 308. Current also flows from the wire 230 over armature 224^c, and wire 284 to lamp 219, which is preferably a white 115 light. The relay 208 will immediately lift its armature to the normal position shown in Fig. 1, but armature 224^a has opened the stick circuit of its relay so that the parts will retain the positions shown in Fig. 6, until 120 the unlocking coil 201 again picks up a current.

The controlled vehicle will continue to run on uncontrolled track without being affected by its own control mechanism. 125

The brake installation.

The brake installation shown in Figs. 2 and 2^A is adapted to be connected to the ordinary air brake systems now in use. 130

These embody the main air reservoir 303, the equalizing reservoir 304, the engineer's brake valve 305, the pipe 306 connecting the main reservoir to the brake valve, the pipe 307 connecting the equalizing reservoir to the brake valve and the train pipe 318. It may be said that the train pipe 318 is filled with air under proper pressure to prevent the application of the brakes and that this pressure is, as a rule, gradually released by manipulating the valve 205 in order that the brakes may be applied gradually. When the brakes are to be released the engineer brings this valve to proper position to again charge the train pipe from the reservoir 303. In the present installation, means are provided for a preliminary partial application of the brakes and a subsequent final application, both being entirely out of the control of the engineer.

The switch 297 is placed between the wires 298 and 299 and this switch is kept closed by air pressure below the piston 300 within the cylinder 301, this pressure being supplied by the pipe 302 connecting to the pipe 306. So long, therefore, as pressure exists in the main reservoir 303, this switch is kept closed, but when the locomotive is in the round house or "dead", this switch is open and thus prevents the main battery 293 being discharged.

As stated before, current passes over the wire 296 to the solenoid 308 so long as the locomotive is not exceeding the proper speed. When this occurs, the circuit to the solenoid is opened and as the solenoid becomes de-energized its armature 309 falls and the valve 310 leaves its position in Fig. 2 and moves to that of Fig. 2A. When this occurs, air flows from the pipe 306 through pipe 302 to valve body 311 and through pipes 312 and 313 to the cylinders 314 and 315. The piston 316 in cylinder 314 is connected to the valve 317 which moves to close the passage from train pipe 318 to the valve 305, thus preventing the engineer from recharging the train pipe while the solenoid 308 is de-energized, but it does not prevent him from discharging this train pipe, this being permitted by the check valve 319.

Attention is called to the valve body 320 in which a valve 321 is slidable. The train pipe 318 normally connects to this valve body through the pipe 322 so that train pipe pressure is had in each of the three small control reservoirs 323, 324 and 325, and by reason of the pipes 326, 327 and 328, this pressure is had in the upper part of the equalizing valve 329, both parts of the diaphragm valves 330 and 331 and in the upper part of the relief valve 332.

When the pressure in the cylinder 315 moves the piston 334 to the right, the end 335 of valve 321 closes the ports to the pipes 322, 327 and 328, thus preventing recharging

of the small control reservoirs 323, 324 and 325. At the same time, the port 336 in the valve 321 is moved out of alignment with the pipe 337 leading to the valve 332, but the port 338 in this valve 321 has been moved to connect the pipe 337 to the calibrated discharge pipe 339. So also the port 340 has been moved to connect the pipe 342 to the pipe 343 leading to the cylinder 344, the pipe 342 having formerly been closed by the valve 321 and the pipe 343 being formerly vented by this port 340 and the discharge opening 345.

When the valve 321 moves to the position shown in Fig. 2A, air will rush from the top of the valve 331 through pipe 342, port 340 and pipe 343 to cylinder 344 and push up the piston 346 to lift the switch 347 to open the circuit to the now de-energized solenoid 308, thus preventing the circuit to this solenoid being closed.

A diaphragm 348 in the valve body 330 carries a stem 349 and a valve 350 is attached to the upper end thereof. A disk 351 on the lower end of this stem engages the spring 352 which normally holds the valve 350 from its seat, the pressure above and below the diaphragm 348 being normally equal because of the pipes 326 and 353. Similarly, the diaphragm 354 in the valve body 331 carries a stem 355, valve 356, disk 357 and spring 358. The diaphragm 359 in valve body 332 carries a valve 360 which closes an opening controlled by a needle valve 361. As this valve is vented at 362, the valve 360 is normally held on its seat by the pressure above the diaphragm and thus prevents flow of air from the control reservoir 325 through the pipe 363.

When the valve 321 is in the position shown in Fig. 2A, air flows from the upper parts of the valve bodies 330, 331 and 332, which are connected by the pipes 364 and 365, through the pipe 337, port 338 and vent 339. Air also flows from the upper part of valve body 329 through pipe 366 to the valve body 320, and through pipe 326 and valve body 330 to the pipe 337. The pressure above the piston 367 is therefore reduced, permitting the pressure below this piston, that is, train pipe pressure, to lift the valve 368 from its seat so as to permit a portion of the train line pressure to escape at 369, which results in a partial application of the brakes.

The pressure above the diaphragm 348 is, however, not sufficiently reduced to permit the pressure in reservoir 324 to overcome the force of the spring 352 which holds the valve 350 off its seat. The pressure in the upper part of the valve body 331 slowly reduces by reason of the pipe 365 so that the excess of pressure below the diaphragm received from the partial reduction reservoir 325 is

soon sufficient to force the valve 356 to its seat, at which time the reduction of pressure in the upper part of the valve body 329 and in the train pipe stops.

- 5 The valve 360 in the valve body 332 is off its seat because the pressure above the diaphragm 359 is reduced, permitting a slow escape of air from the partial reduction reservoir 325 which escape is controlled by
 10 the needle valve 361. As soon as the pressure in this reservoir 325 has fallen below what is sufficient to overcome the force of the spring 358, then the valve 356 is again pulled down, allowing a further escape of
 15 air from the pipe 364, valve body 330, pipes 326 and 366 and top of valve 329. This again results in a reduction of pressure in the train pipe and a further application of the brakes.
 20 As soon as the pressure above the diaphragm 348 in valve body 330 is reduced sufficiently to permit the pressure in the control reservoir 324 and below the diaphragm 348 to overcome the force of the spring 352,
 25 the valve 350 will be forced to its seat, thus stopping this reduction of train pipe pressure. The first or partial application of the brakes depends upon the strength of the spring 358 and the second or complete application on the strength of the spring 352.

The length of time between partial and complete application of the brakes is controlled by the needle valve 361 and the force or rapidity of the application by the calibrated opening or port 339. The reservoir 323 simply stores a large amount of air so that the opening at 339 can be made relatively large. If this reservoir were not present, the escape opening at 339 would necessarily be very small in order to secure a reasonable time interval between the partial and complete application of the brakes. But the large excess of air in reservoir 323 renders this minuteness unnecessary.

45 A valve body 370 is provided with a diaphragm 371 connected by a stem 372 with a valve 373. A pipe 374 connects to the pipe 307 and equalizing reservoir 304. Another valve body 375 has a diaphragm 377 connecting to a valve 378 and a disk 379 by means of a stem 376. A spring 380 below this disk tends to hold the valve 378 on its seat. But when the train pipe pressure is reduced as above described, pressure in the pipes 313 and 382 forces down the diaphragm 371 and valve 373 permitting air of equalizing tank pressure to flow from the pipe 307 through pipe 374, valve body 370, pipe 384, into valve body 375, forcing down the diaphragm 377 and valve 378 and flowing up pipe 385 into cylinder 386 where it forces the piston 387 to open the switch 388, thus opening the circuit to the solenoid 308 at another point.

The brakes are now fully applied and the

circuit to the solenoid 308 is open at 347 and 388. When the valve 350 is finally forced to its seat by the pressure in tank 324, air will flow backward from the cylinder 344 through pipe 343, port 340, pipe 342, valve 331, pipes 365 and 337 and port 338 to the vent 339, the piston 346 will slide down and the switch 347 will close.

The normal circuit of solenoid 308 is from the battery over wires 292, 225, and 230, armature 224^c wire 235, armature 222^c, wires 243 and 244, armature 224^b, and wire 296 to the solenoid, thence by way of switches 347 and 348, wire 299, switch 297 and wire 298 to the battery.

The valve 378 left its seat when the pressure in the train pipe 318 and in pipe 390 was reduced by escaping at 369, which also occurred when the downward pressure on the valve 378 became greater than the pressure below it. The final result was that the piston 387 was held up by pressure from the equalizing reservoir 304. The piston 387 is slightly loose so that there is a slight leak. After the switch 347 has been closed the engineer places his valve 305 in "lap" position, at which time there is escape of air from reservoir 304 through the pipe 374, valve 370, pipe 384, valve 375, pipe 385 and cylinder 386 around the piston 387, until the pressure in reservoir 304 is as low or lower than in the train pipe. This permits the spring 380 to move the valve 378 to its seat and the leakage at the piston 387 permits the switch 388 to close.

It will therefore be seen that the engineer has no control over the braking mechanism except that he may bring the speed of his train down to that predetermined for "caution" or "danger" immediately upon receiving proper signals at the lamps 217-218. Should he neglect to do this, the brakes will be applied and the train must come to a stop for the switch 347 will not close until an appreciable time after the completed braking operation is completed.

The details of the construction of these control installations and of the mechanism on the locomotive may all be changed by those skilled in the art without departing from the spirit of our invention as set forth in the following claims.

We claim:

1. In an automatic train control system, a series of collector coils mounted on a vehicle adjacent the track to take up high-frequency currents of different wave-length tuning condensers and high-frequency relays connected to said coils to differentiate the wave lengths and respond thereto, a normally energized brake control device and circuits thereto, and electro-responsive means controlled by said high-frequency relays, one of said loops and the condenser and

- high-frequency relay connected thereto and the electro-responsive means controlled thereby serving to break the circuits to the other electro-responsive means.
5. 2. In an automatic train control system, a normally energized brake control device, a plurality of circuits corresponding to different permissive speeds for the vehicle and each effective to maintain said brake control device energized, speed-responsive means governed by the actual speed of the vehicle for opening said circuits, neutral relays controlling the said circuits, a plurality of loops mounted on the vehicle adjacent to but spaced from the track and adapted to receive high-frequency currents from the track, and adjustable condensers and high-frequency relays connected to the coils to control the action of said neutral relays, three of the neutral relays being stick relays whose holding circuits are adapted to be opened by a fourth neutral relay.
10. 3. In an automatic train control system, a series of collector coils mounted on a vehicle adjacent the track to take up high-frequency currents of different wave lengths, tuning condensers and high-frequency relays connected to said coils to differentiate the wave lengths and respond thereto, a normally energized brake control device and circuits thereto, electro-responsive means controlled by said high-frequency relays, and speed responsive means connected to moving parts of the vehicle for opening two of said circuits to the brake control device in succession as the speed of the vehicle increases, one of said loops, condensers and high-frequency relays receiving current from the track, as the train passes from a controlled to an uncontrolled portion of the track, and adapted to release movable parts which close an independent circuit to the brake control device.
15. 4. In a train control system, the combination of a track divided into blocks, two generators for high-frequency control currents for each block, means to vary the wave length of the current from one of said generators, conductors connecting said generators to the track, a source of operating current for said generators, and a relay controlled by a vehicle when in said block to close the circuit between the source and the generators.
20. 5. In a train control system, the combination of a track divided into blocks, two generators for high-frequency control currents for each block, means to vary the wave length of the current from one of said generators, conductors connecting said generators to the track, a source of operating current for said generators, and a relay controlled by a vehicle when in said block to close the circuit between the source and the generators, said variable generator being connected to both tracks of the block and the other to only one of the tracks.
25. 6. In a train control system, the combination of a track divided into blocks, two generators for high-frequency control currents connected to the exit end of each block, means controlled by the presence of a vehicle in the second block ahead to vary the wave length of current of one of the generators which is connected to both rails of the track, the other generator being connected to a single rail, a battery connected to the rails at the entrance end of the block and a relay energized thereby at the exit end of the block, and armatures for said relay to control the operations of said generators.
30. 7. In a train control system, the combination of a track divided into blocks, two generators for high-frequency control currents connected to the exit end of each block, means controlled by the presence of a vehicle in the second block ahead to vary the wave length of the current of one of the generators which is connected to both rails of the tracks, the other generator being connected to a single rail, a battery connected to the rails at the entrance end of the block and a relay energized thereby at the exit end of the block, armatures for said relay to control the operations of said generators, and a track signal system embodying a series of normally inoperative electric lamps, normally open circuits to said lamps, means depending upon the condition of the track ahead to select one of the lamps for operation, the circuit to said lamp being closed by the armatures of said relay.
35. 8. In a train control system, a track divided into blocks and a vehicle thereon, generators of high-frequency current connected to the rails of the blocks, means controlled by the condition of the track ahead to vary the wave length of the current from one of the generators, the current from the other generator having constant wave length differing from those of the variable generator, collector coils mounted on the vehicle adjacent the track, one for each wave length, a normally energized brake control system on the vehicle, a series of circuits therefor, a collector coil mounted on the vehicle for each wave length, and means responding to each wave length to control the opening and closing of said circuits.
40. 9. In an automatic train brake control system, collector coils and relays connected thereto responsive to high-frequency currents in the rails to hold the brake control mechanism inoperative, and an additional coil and a relay connected thereto, which, when responding to a selected high-frequency current, is adapted to render the first named coils and relays inoperative.
45. 10. In an automatic train brake control

- system embodying a train control valve and electro-mechanical means to hold it closed, a current source and circuits between it and said valve, collector coils and relays connected thereto responsive to high-frequency currents in the rails to hold closed a plurality of said circuits according to the currents received by said coils, and an additional collector coil and a relay connected thereto, which, when responding to a selected high-frequency current, is adapted to render said first named coils and relays inoperative and close another of said circuits between the current source and valve. 10
11. In an automatic train control system, the combination of a track divided into blocks, a control installation to propagate high-frequency current of different wave lengths in the rails of each block, a signal installation embodying lamps of different colors at one end of each block, means, including wires extending between adjacent signal installations, controlled by the presence or absence of a vehicle in the three blocks in advance to select the signal lamp, and means, including wires extending between adjacent control installations, controlled by the presence or absence of a vehicle in the three blocks in advance to 15
- select the wave length of the current propagated by a control station. 30
12. In a train control system, the combination of a normally energized brake control apparatus, two circuits corresponding to different permissible speeds for the vehicle and each effective to maintain said brake control device energized, speed-responsive means governed by the actual speed of the vehicle to open either of said circuits, a collector coil for each of said circuits and mounted on the vehicle adjacent the trackway to receive high-frequency current of a predetermined wave length, means connected to each coil and affected by the current taken up thereby to open and close one of said 45 circuits, a third collector coil mounted on the vehicle adjacent the trackway to receive high-frequency current of another wave length, and means connected to said last named coil adapted to render operative the first named collector coils and the means connected thereto while said last named coil receives current and to prevent change in said circuits to the brake control device when no current is received by said last named 50 coil. 55
